 Company, Midland, Mich., a corporation of
 Delaware

Application May 30, 1945, Serial No. 596,710

2 Claims. (Cl. 266—19)

1

This invention relates to apparatus for the distillation of metals. It particularly concerns improved means for disposing the feed metal in the vaporizing zone in the form of a continuously flowing thin film.

A number of metallurgical processes involve distilling a desired metal from an alloy thereof with less volatile metals. In certain of these processes, the purity of the product is affected very materially by the manner in which the alloy is disposed on the heated vaporizing surfaces in the still. This effect is most pronounced in the vacuum distillation of alloys of high density.

Thus, the volatilization of metals from dense alloys takes place largely by surface evaporation. Boiling, meaning the formation of vapor bubbles in the body of the metal, is restrained by the high hydrostatic pressures which exist at all points below the surface. Boiling may occur, however, when the alloy is heated drastically. In such a case, the action is usually so violent that there is a serious entrainment of the boiling alloy in the evolving vapors, with a corresponding decrease in the purity of the distilled product. In designing a still for vaporizing metals, then, one of the major problems is to provide means for disposing the feed alloy in a form such that it will present a maximum surface area for the disengagement of vapor and yet will not be subject to such overheating as produces violent boiling.

One solution to the problem is to arrange in the vaporizing section of the still a number of superposed trays which hold the metal as a series of pools through which it flows while it is being heated. Unfortunately, since in this design structural limitations usually require that the trays be of substantial depth, stagnation of a part of the metal invariably occurs. In addition, since the ratio of vapor-disengaging surface of the metal to total metal volume is small in the case of deep trays, adequate vaporizing rates can only be obtained either by going to a still which has a considerable number of trays, and hence is of excessive size, or by overheating the metal to induce violent boiling, in which case the distilled product is contaminated with entrained feed alloy. In addition, if the feed contains solid matter in suspension, the trays tend to fill up and lose their effectiveness. For these reasons, tray boilers, although perhaps the most usual form of metal vaporizer, leave much to be desired.

It is, therefore, an object of the present invention to provide an improved metallurgical still in which the ratio of vapor-disengaging area to metal volume is large, so that high vaporizing

2

rates can be realized without overheating the feed to the point that boiling and its resulting entrainment of alloy in the vapor occur. Another object is to provide a still in which no part of the feed alloy can become stagnant, and in which molten metals containing solid matter in suspension can be handled without difficulty.

In metallurgical stills according to the invention, the feed alloy is introduced into a shallow spiral trough which slopes continuously down the vaporizing section of the still. During its traverse of the trough, the alloy is heated to a distilling temperature and evolves vapors of the volatilizable component rapidly and effectively without undergoing ebullition. Because of the slope of the trough, the alloy is in continuous flow at all times while it is being heated. As a result, all portions of the heated metal are repeatedly brought to the vapor-disengaging surface of the flowing stream to release their volatilizable component; stagnation does not occur. In addition, solid particles entering with the feed are washed through to the outlet by the moving metal; the still is thus to a large extent self-cleaning.

25 The invention may be further explained with reference to the accompanying drawings, in which:

Fig. 1 is a vertical assembly, largely in cross-section, of one form of metallurgical still embodying the invention;

Fig. 2 is a vertical cross-section of a portion of the vaporizing zone of a still embodying another form of the invention; and

Fig. 3 is a fragmentary perspective view of the construction shown in Fig. 2.

The apparatus may be described with reference to the distillation of magnesium from a lead-magnesium alloy in which lead preponderates, although it is to be understood that the invention is not thus limited.

30 In the equipment of Fig. 1, the liquid lead-magnesium alloy to be distilled is stored in an alloy steel tank 4 surrounded by insulating brick 5. The alloy is withdrawn by a sump pump 6 driven by a variable-speed motor 7 and is forced through a feed line 8 into the top of the vaporizing section of the still 9.

This still is constructed of a large-diameter alloy steel pipe set vertically and provided at the lower end with a conical bottom 10 from which a drain pipe 11 extends into the reservoir 4. At the upper end, the still is closed by a flanged dome 12 from which a vacuum line 13 leads to an exhaust pump 14, the line being provided with a clean-out flange 15. The still is divided into a

lower vaporizing section 16 and an upper condensing section 17, the two zones being separated by radiation shielding baffles 18. The vaporizing section 16 is set in a brick furnace 19 heated by gas burners 20, and the condenser 17 is cooled externally by an air-circulating jacket 21.

Mounted within the vaporizing section 16 of the still is a truncated graphite conical pillar 22, formed, for convenience, of three pieces held together by dowels 23. The pillar rests on a graphite plate 24, which fits snugly into the bottom piece 10 and is provided at its edge with one or more drain holes 25, and is secured at the top by alloy steel hold-down lugs 26 welded to the wall of the still. A cup 27 is formed in the top of the pillar 22 to receive alloy issuing from the feed pipe 9.

In the side of the pillar 22, there is cut a spiral alloy-carrying trough 28, starting at the cup 27 and continuing at a smooth slope until it runs out at the bottom just above the support plate 24. The precise cross-sectional shape of the trough is not critical, but it is highly desirable that its depth be a minor fraction of its width, i. e. that the trough be as shallow as possible. It is likewise preferable that the downward slope of the trough be gentle, which is achieved by cutting the spiral with a pitch which is a minor fraction of the diameter of the pillar 22, as shown in Fig. 1. The base diameter of the pillar should ordinarily be nearly equal to the inside diameter of the still, while the top diameter is preferably a major fraction of the still diameter.

Magnesium vapors generated in the vaporizing section 16 escape upwardly into the condensing section 17, where they come into contact with the cooled walls and are condensed to liquid magnesium. The condensate trickles down into an annular collecting gutter 29 welded to the wall of the condenser at the bottom, and from there runs through a product line 30 into a holding pot 31 set in brickwork 32 and fired by a gas burner 33.

The alloy tank 4 and condenser 17 are provided with heaters as shown, and the associated pipes 8, 11 and 30 with heaters, not illustrated, to raise them to the appropriate temperatures when beginning operation. These parts are also jacketed with thermal insulation, not shown, to prevent freezing of the lead-magnesium alloy and the magnesium product once circulation is established.

In operation of the apparatus shown in Fig. 1, the lead-magnesium alloy in the tank 4 is kept under a protective saline flux or inert gas atmosphere. The tank 4 and feed line 8 are maintained at a temperature above the freezing point of the alloy, preferably at 550° to 600° C. The burners 20 are adjusted to maintain the lower section 16 of the still at a vaporizing temperature, usually 775° to 875° C., and the cooling air to the condenser 17 is controlled so that the temperature of the magnesium condensate is above its freezing point (651° C.), preferably 655° to 665° C. The exhaust pump 14 is operated to hold the still at a pressure which is sufficiently reduced to permit boiling to take place at a high rate, but is above the vapor pressure of the magnesium condensate; absolute pressures between 0.1 and about 0.5 inch of mercury are most satisfactory. At this pressure, the alloy in the feed line 8 and the return drain 11, and the magnesium in the product line 30 rise to levels well above those of the tank 4 and pot 31, forming barometric seals.

The motor 7 is adjusted so that the pump 6 forces lead-magnesium alloy at a desired rate into the still, where it falls into the cup 27. The alloy then flows continuously down the convolutions of the spiral trough 28 and finally through the openings 25 and out the drain 11, being at the same time heated by radiation from the hot wall 16 and by contact with the pillar 22 which is itself heated by radiation. As the alloy passes down the trough 28, part of the magnesium in it is vaporized without appreciable occurrence of ebullition and with little, if any, entrainment of the alloy. The vapors rise into the condenser 17 where they are condensed to liquid magnesium, which leaves as product through the line 30.

The alloy in the tank 4, which would otherwise become depleted in magnesium as operation proceeds, is enriched continuously with a material rich in magnesium from a source not shown.

The purpose of the conical shape of the pillar 22 illustrated is to provide an increasing area for vapor flow from bottom to top of the vaporizing section 16. To this end the pillar might equally well be conoidal. Less advantageously, it may be cylindrical, in which case its diameter would have to be considerably less than that of the still.

The use of graphite or other carbon as a material of construction for the pillar 22 is preferred because of its inertness to thermal shock, its high emissivity, which is important where the pillar is to be heated by radiation, and the fact that it does not corrode with introduction of undesired substances into the flowing alloy. However, the pillar may, in some instances, be made of other materials, such as alloy steel or ceramic brick.

In an alternative construction according to the invention, the spiral metal-retaining trough, instead of being formed on a central pillar within the still, is located adjacent to the inside wall of the still and receives heat by conduction. As illustrated in Figs. 2 and 3, the trough 34 is formed of a continuous strip 35 of alloy steel which is set at a slight angle to the horizontal to provide a shallow gutter and which winds helically down the still. For convenience in construction, the trough assembly is preferably made up of a cylindrical sleeve 36 which slides snugly into the still and to the inside of which the spiral strip 35 is welded. The sleeve and associated trough are preferably made up in a number of identical sections which are slipped into the still body through the top and are superposed within the vaporizing section of the still to form a continuous spiral trough of any desired height. (One such section is shown in Fig. 2.)

In operation of the still of Figs. 2 and 3, the alloy feed is introduced into the upper end of the trough 34 and circulates downwardly through the still, being heated from the hot wall 16 and vaporizing its volatile component. The vapors rise through the open central core and escape into the condenser 17.

It is to be understood that the foregoing description is illustrative rather than strictly limitative, and that the invention is co-extensive in scope with the following claims.

What is claimed is:

1. In a still for the vacuum distillation of a volatile metal from a molten alloy thereof: a vertical elongated thermally-conductive closed still body having therein a vaporizing zone and a con-

densing zone in communication with each other, means for evacuating the still body, means for cooling the condensing zone, a furnace surrounding the still body at the vaporizing zone for raising the latter to a distilling temperature by heat applied externally to the still body, a conical pillar mounted axially in the still body within the vaporizing zone and having formed in the outer surface thereof a shallow open spiral trough extending in a continuous downward slope from the upper to the lower part of the zone, means for introducing the alloy to be distilled into the upper part of the trough and for collecting residual alloy flowing from the bottom of the trough, and means for withdrawing condensate from the condenser.

2. A still according to claim 1 wherein the pillar is constructed of graphite.
